UNITED STATES PATENT OFFICE

2,546,612

COMPRESSOR REGULATOR

Win W. Paget, Michigan City, Ind., assignor to
 Joy Manufacturing Company, a corporation of
 Pennsylvania

Application October 20, 1945, Serial No. 623,487

12 Claims. (Cl. 230—3)

1

My invention relates to mechanisms for regulating the operation of compressors, and more particularly to mechanisms for varying the speed of operation and effecting loading and unloading of compressors in accordance with discharge pressures.

In order that a highly efficient operation of a compressor may be obtained, the driving speed of the compressor is usually reduced gradually as its discharge pressure increases through a predetermined pressure range. As the pressure increases above the upper limit of the range, the speed may be maintained constant until a maximum desired pressure is reached, at which time the compressor is unloaded and slowed down to an idling speed. On reduction in the pressure from the maximum value to a predetermined lower value, the compressor is speeded up and then reloaded.

A mechanism for regulating the speed of a compressor and controlling the operation of an unloading means therefor may desirably include a control member which is movable to different angular positions for regulating the supply of operating fluid to an engine driving the compressor. Fluid actuated devices pivotally connected to the control member at spaced points operate to vary the angular position of the latter. One of the fluid actuated devices is subjected continuously to the pressures in a receiver to which fluid is supplied by the compressor and operates on increase in the pressure through a given range for swinging the control member about its pivot connection to the other pressure responsive device in a direction to effect a slowing down of the engine. The swinging of the control member by the first fluid actuated device is limited, and a valve actuated by the device as it moves the control member to its upper limit permits fluid to flow to the second fluid actuated device for swinging the control member about its pivot connection to the first fluid actuated device and effecting a slowing down of the engine to an idling speed. Fluid is permitted to flow at the same time to the unloading means for effecting an unloading of the compressor.

In another form of the regulating mechanism, the control member is pivotally connected to a fixed support in place of the second fluid actuated device, and the valve actuated by the first fluid actuated device permits fluid to flow to an unloading means and to a separate device which operates to reduce the supply of operating fluid to the engine.

An object of my invention is to provide an im-

2

proved mechanism for regulating the operation of a compressor. Another object is to provide an improved mechanism which is operative to regulate the speed of a compressor and to control the loading and unloading of the latter. Still another object is to provide an improved regulating mechanism having a member movable to different positions by fluid actuated devices for varying the speed of an engine and having valve means actuated by one of said devices for controlling the flow of fluid to another of said devices. Yet another object is to provide an improved regulating mechanism having a member movable by a fluid actuated device for varying the speed of an engine and having a valve actuated by said device for controlling the flow of fluid to an unloading means for a compressor driven by said engine. Still another object is to provide an improved mechanism for varying the speed of an engine driving a compressor in accordance with the compressor discharge pressure and effecting at a predetermined maximum pressure an unloading of the compressor and a slowing down of its driving engine to an idling speed. Other objects will appear in the course of the following description.

In the accompanying drawings I have shown for purposes of illustration two forms which my invention may assume in practice.

In these drawings:

Fig. 1 is a side elevational view of an engine and one form of my improved regulating mechanism associated therewith.

Fig. 2 is an enlarged vertical sectional view of the regulating mechanism shown in Fig. 1.

Fig. 3 is a cross-sectional view taken on the planes of the line 3—3 of Fig. 2.

Fig. 4 is a cross-sectional view taken on the plane of the line 4—4 of Fig. 2.

Fig. 5 is a central sectional view through the cylinder head and a portion of the cylinder of a compressor adapted to be driven by the engine of Fig. 1.

Fig. 6 is a schematic diagram showing the regulating mechanism of Fig. 1 connected into a control system for a compressor and its driving engine.

Fig. 7 is a schematic diagram showing a slightly modified form of the regulating mechanism connected into a different control system for a compressor and its driving engine.

There is shown in Figs. 1 to 6 one form of my improved regulating mechanism associated with an internal combustion engine for controlling the supply of operating fluid to the latter in accord-

ance with pressures in a receiver to which fluid is supplied by a compressor driven by the engine. The internal combustion engine, generally designated 1, has a throttle valve 2 which is regulated by my improved regulating mechanism, generally designated 3. The power shaft of the engine is connected by means, not shown, to a compressor, one piston 5 of which is shown as being reciprocable in a bore 6 of a compressor cylinder 7. The compressor, as indicated by portions of cylinder head members 8, 8 in Fig. 6, is provided with two cylinders, but it will be understood that a compressor having a different number of cylinders may be used if desired. Fluid is admitted through an intake passage 9 and past an inlet valve 10 to the cylinder bore 6 where it is compressed and then discharged past a discharge valve 12 to a passage 13 which is connected by suitable connections, not shown, to a receiver 14, shown in Fig. 6. The cylinder head member 8 is provided with a chamber 16 which receives a piston 18 acting against a plate member 19. Rods 20 are connected to the plate member 19 and extend through openings in the cylinder head to engage the inlet valve 10 for unseating the latter and effecting an unloading of the compressor when the piston 18 is subjected to pressure fluid. The piston 18 is normally held in its raised position by a spring 22 and is adapted to be forced to its lower position against the action of spring 22 by pressure fluid supplied to the chamber 16 through a conduit 24.

My improved regulating mechanism 3 is adapted to be connected to the side of the engine 1 by any suitable means and comprises a cylindrical shaped member 26 having a bore 21 which reciprocably receives a piston 28. Received in a space 30 at the head end of the cylinder member is a bellows device 31 acting against the piston 28 and operating to move the piston against the action of a spring 32 when pressure fluid is supplied thereto. Connected to the piston is a piston rod 33 extending through an opening in a plate member 35 which is adjustably connected, as by bolts 36, to a flange portion 37 on the cylinder member and has a portion 38 acting as an abutment for the spring 32. Extending through a diametrical slot 40 in the piston rod is a control member 41 which is pivotally connected at 42 to the piston rod and is connected at its upper end to a rod 44 which is connected to an arm 45 adapted to operate the throttle valve 2.

A member 46 having leg portions 47, 47, as shown in Fig. 3, is so arranged that the leg portions lie on opposite sides of the control member 41 and permit the piston rod to move longitudinally between them. Flange portions 48 formed on the ends of the leg portions are connected, as by screws 49, to the cylinder member 26 for holding the member 46 in place. An outer body portion 51 of the member 46 is provided with bores 52 and 53 extending in axial alignment with the piston rod and connected in communication with each other by a port 54. A ball valve 55 is received in the bore 53 and is yieldingly urged by a spring 56 into engagement with a seat surrounding the port 54 for cutting off communication between the bores. A plug 58 threaded into the outer end of the bore 53 provides an adjustable abutment for the spring 56, and a passage 59 extending axially through the plug conducts fluid from a conduit 60 to the bore 53. Threaded into the bore 52 is a valve cage 62 having an axial bore 63 in which an

elongated valve member 64 is reciprocably received. The outer end of the valve member 64 is adapted to be engaged by the piston rod 33 as the latter is moved to the right in Fig. 2, and a stem 65 formed on the valve member operates to unseat the ball valve 55 when the valve member is moved by the piston rod. Surrounding a portion of the valve member is a chamber 67 connected by ports 68 and 69 in communication with the atmosphere and connected by a port 70, through which the stem 65 extends, with the inner end of the bore 52. The valve member 64 is adapted to engage a seat surrounding the port 70 when it is moved to a position unseating the ball valve 55 and cut off communication between the inner end of the bore 52 and the chamber 67 through the port 70.

Formed on the member 46 is a boss portion 72 having a bore 73 reciprocably receiving a piston 74. A piston rod 75 formed on the piston 74 extends through a member 76 threaded into the bore 72 and is pivotally connected at 77 to the control member 41 at a point below the pivot point 42. A spring 78 acts between the member 76 and the piston 74 for urging the latter toward the inner end of the bore 73. A screw 80 threaded through an opening in the boss portion 72 into the bore 73 acts as an adjustable abutment for the piston 74. A cap 81 threaded on the outer end portion of the screw 80 acts as a guard for the latter. Formed in the member 46, as shown in Fig. 4, is a passage 82 which connects the bores 52 and 73 in communication with each other and which is connected, Figs. 4 and 6, by a conduit 84 and the conduits 24 in communication with the cylinder head members 8, 8 for conducting fluid relative to the compressor unloading devices. Connected into the conduit 84 is a device 86 of a standard make operating to permit a free flow of fluid toward the unloading devices and to restrict the flow of fluid in the opposite direction. The conduit 60 is connected to the receiver 14 for supplying pressure fluid to the bore 53, and the bellows device 31 has pressure fluid supplied continuously thereto by a conduit 88 leading from the receiver and opening through a cover plate 89 into the bellows device.

Pressure fluid supplied to the bellows device 31 operates to expand the latter and move the piston 28 when the pressure reaches a value sufficient to overcome the spring 32. The tension of the spring may be varied by adjusting the plate member 35 providing an abutment for the spring. As the piston is moved by the bellows device, the control member 41 swings about the pivot connection 77 and moves the rod 44 in a direction to effect a closing movement of the throttle valve 2. Continued movement of the piston results in an engagement of the piston rod 33 with the valve member 64 which holds the piston against further movement by the bellows device 31 until the pressure increases to a value sufficient to move the valve member and unseat the ball valve 55 against the action of the receiver pressure and the force of the spring 56. The speed of the engine remains constant while the valve member 64 prevents movement of the control member by the piston. When the pressure reaches the value necessary for unseating the ball valve, the valve member 64 moves to a position unseating the ball valve and cutting off communication between the bore 52 and the atmosphere through port 70. Pressure fluid then flows past the ball valve to the bore 52 where it enters the passage 82 and is conducted to the bore 73 and the conduit 84 lead-

ing to the unloading devices for the compressor. The device 86 in the conduit 84 permits a free flow of fluid to the unloading devices so that an immediate unloading of the compressor takes place. The fluid supplied to the bore 73 acts on the piston 74 and moves the latter to swing the control member 41 about the pivot point 42 in a direction to effect a further closing movement of the throttle valve, the movement of the piston to its outermost position causing the throttle valve to be so positioned that the engine operates at an idling speed.

When the ball valve is unseated, the force acting to seat this valve is only that of the spring 56. The receiver pressure supplied to the bore 52 acts, however, on the valve member 64 over an area equal to that of the port 78 and tends to force the valve member outwardly. The area of the port 78 is somewhat less than that of the port 54 so that the total force acting on the valve member is substantially less when the ball valve is unseated than when it is seated. The pressure must then drop a substantial amount before the piston 28 is moved against the action of the bellows device 31. As soon as this pressure drop takes place, the valve member 64 moves outwardly venting fluid from the unloading devices and the piston 74 through the ports 68 and 69 and permitting the ball valve 55 to seat and cut off the flow of fluid to the bore 52. The spring 78 acting on the piston 74 then causes the latter to move in a direction to swing the control member 41 about the pivot point 42 and open the throttle valve to increase the speed of the engine. The venting of fluid from the unloading devices is delayed, however, by the device 86 so that reloading of the compressor does not take place until its speed has been increased.

In the form of the invention shown in Fig. 7, the engine 1 is provided with two throttle valves 90 and 91, the valve 90 being regulated by a speed governor 92 and having an operating arm 93 which is connected by a spring 94 to the upper end of the control member 41. The regulating mechanism 3 is like that of the first form of the invention except that the fluid actuated means connected to the lower end of the control member in the first form is omitted and lugs 95 formed on the leg portions 41 provide instead a stationary pivot point 96 for the lower end of the control member. Connected in the conduit 84 is a device 98 which controls the flow of fluid relative to the unloading devices in the same manner as the device 86 and also provides a connection for a conduit 99 leading to a fluid actuated device 100. A rod 102 connects an operating arm 103 for the valve 91 to an arm 104 operatively connected to the fluid actuated device 100 in a manner to swing in a direction to close the valve 91 and effect an operation of the engine at an idling speed when pressure fluid is supplied to the device 100. The connection provided by the device 98 for the conduit 99 is such that fluid may flow freely in both directions between the conduits 84 and 99. A manually operated lever 106 is provided for regulating the valve 91 and may be held in any desired position by a wing nut 107. The device 100 is shown herein as having a projecting portion 108 supporting an adjustable abutment member 109 for the control member 41.

In this form of the invention the control lever 41 swings about the pivot point 96 in a clockwise direction as the receiver pressure increases through a predetermined range and reduces the tension on the spring 94, thereby permitting the

speed governor to operate and reduce the speed of the engine. When the ball valve 55 of the regulating mechanism is unseated pressure fluid flows to the conduit 84 and passes immediately to the unloading devices for unloading the compressor and to the device 100 for actuating the valve 91 to slow down the engine to an idling speed. When the receiver pressure drops and the regulating mechanism operates to vent the conduit 84, fluid flows freely from the device 100 so that the latter operates to open the valve 91 and speed up the engine, but the flow from the unloading devices is restricted so that the compressor is brought up to speed before reloading takes place.

As a result of my invention an improved mechanism is provided for controlling the loading of a compressor and its speed of operation.

While there are in this application specifically described two forms which the invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. A regulating mechanism for an engine driven compressor comprising, in combination, a control member, means operatively connecting said control member to a fuel regulating means for the engine, a pair of pressure responsive devices connected to said control member and each operative by pressure fluid supplied thereto to move said control member about its connection with the other in a direction to effect a reduction of fuel supply to the engine, means for subjecting continuously one of said pressure responsive devices to the pressures in a receiver connected to the compressor, and means for controlling the pressure acting on the other of said pressure responsive devices including a valve member movable by said one of said pressure responsive devices for controlling and a passage for operating fluid for the other of said pressure responsive devices extending between the latter and said valve member.

2. A regulating mechanism for an engine driven compressor comprising, in combination, a control member, means operatively connecting said control member to a fuel regulating means for the engine, a pair of pressure responsive devices connected to said control member and each operative by pressure fluid supplied thereto to move said control member about its connection with the other in a direction to effect a reduction of fuel supply to the engine, means for subjecting continuously one of said pressure responsive devices to the pressures in a receiver connected to the compressor, means for supplying pressure fluid from said receiver to the other of said pressure responsive devices, and means including a valve member adapted to be actuated by said one of said pressure responsive devices for controlling the flow of fluid in said fluid supply means, said valve member movable to a position permitting fluid flow to the other of said pressure responsive devices as said control member is moved to a predetermined position by said one of said pressure devices.

3. A regulating mechanism for an engine driven compressor having fluid actuated unloading means comprising, in combination, a control member, means operatively connecting said con-

trol member to a fuel regulating means for the engine, a pair of pressure responsive devices pivotally connected to said control member at points spaced longitudinally thereof different distances from said connecting means and each operative by pressure fluid supplied thereto to swing said control member about its pivotal connection to the other in a direction to effect a reduction of fuel supply to the engine, means for supplying pressure fluid continuously to one of said pressure responsive devices from a receiver connected to the compressor, and means for controlling the pressure acting on the other of said pressure responsive devices and the unloading means including a valve member actuated by said one of said pressure responsive devices and passage means for pressure fluid extending between said valve member and each of said other of said pressure responsive devices and said unloading means.

4. A regulating mechanism for an engine driven compressor comprising, in combination, a control member, means operatively connecting said control member to a fuel regulating means for the engine, a pair of pressure responsive devices operatively connected to said control member and each operative by pressure fluid supplied thereto to move said control member about its operative connection with the other in a direction to effect a reduction of fuel supply to the engine, means for subjecting continuously one of said pressure responsive devices to the pressures in a receiver connected to the compressor discharge, means for controlling the pressure acting on the other of said pressure responsive devices including a valve member movable by said one of said pressure responsive devices after predetermined movement of said control member and a passage for operating fluid for the other of said pressure responsive devices extending between the latter and said valve member, means for subjecting said valve member to a pressure opposing its movement by said one of said pressure responsive devices, and means for subjecting said valve member to a lesser opposing pressure after movement by said one of said pressure responsive devices.

5. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device operatively connected to said control member and operable by pressure fluid supplied thereto to actuate said pivoted control member to effect a reduction in fuel supply to the engine, means for continuously supplying fluid discharged by the compressor to said pressure responsive device, and valve means controlled by said pressure responsive device and arranged in line with the axis of the latter for controlling the flow of actuating fluid between itself and the compressor unloading means.

6. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device operatively

connected to said control member and operable by pressure fluid supplied thereto to actuate said pivoted control member to effect a reduction in fuel supply to the engine, means for continuously supplying fluid discharged by the compressor to said pressure responsive device, and valve means controlled by said pressure responsive device and seating in a direction towards the latter for controlling the flow of actuating fluid to the compressor unloading means.

7. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device operatively connected to said control member and operable by pressure fluid supplied thereto to actuate said pivoted control member to effect a reduction in fuel supply to the engine, means for continuously supplying fluid discharged by the compressor to said pressure responsive device, and valves controlled by said pressure responsive device and arranged in line with the axis of the latter and respectively controlling the flow of actuating fluid to and the venting of fluid from the compressor unloading means.

8. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device for moving said control member and operable by pressure fluid supplied thereto to actuate said pivoted control member to effect a progressive reduction in fuel supply to the engine, means for continuously supplying fluid discharged by the compressor to said pressure responsive device, a second pressure responsive device for moving said control member and operable by pressure fluid supplied thereto further to actuate said pivoted control member to effect a reduction in fuel supply to the engine to cause operation of the latter at an idling speed, and valve means controlled by said first pressure responsive device and arranged in line with the axis of the latter for controlling the flow of fluid between itself and said second pressure responsive device.

9. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device for moving said control member and operable by pressure fluid supplied thereto to actuate said pivoted control member to effect a progressive reduction in fuel supply to the engine, means for continuously supplying fluid discharged by the compressor to said pressure responsive device, a second pressure responsive device for moving said control member and operable by pressure fluid supplied thereto further to actuate said pivoted control member to effect a reduction in fuel supply to the engine, means for continuously supplying fluid discharged by the compressor to said pressure responsive device, a second pressure responsive device for moving said control member and operable by pressure fluid supplied thereto further to actuate said pivoted control member to effect a reduction in fuel supply to the engine to cause operation of the latter at an idling speed,

and valve means controlled by said first pressure responsive device and arranged in line with the axis of the latter for controlling the flow of fluid between itself and each of said second pressure responsive device and said fluid actuated unloading means.

10. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device for moving said control member and operable by pressure fluid supplied thereto to actuate said pivoted control member to effect a progressive reduction in fuel supply to the engine, means for continuously supplying fluid discharged by the compressor to said pressure responsive device, a second pressure responsive device for moving said control member and operable by pressure fluid supplied thereto further to actuate said pivoted control member to effect a reduction in fuel supply to the engine to cause operation of the latter at an idling speed, and valve means controlled by said first pressure responsive device and having an operating plunger coaxial with the latter for controlling flow of fluid between itself and said second pressure responsive device.

11. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device for moving said control member and operable by pressure fluid supplied thereto to actuate said pivoted control member to effect a progressive reduction in fuel supply to the engine, means for continuously supplying fluid discharged by the compressor to said pressure responsive device, a second pressure responsive device for moving said control member and operable by pressure fluid supplied thereto further to actuate said pivoted control member to effect

a reduction in fuel supply to the engine to cause operation of the latter at an idling speed, and valve means controlled by said first pressure responsive device and having an operating plunger coaxial with the latter for controlling flow of fluid between itself and each of said second pressure responsive device and said fluid actuated unloading means.

12. A regulator for an internal combustion engine driven compressor of which the engine has associated therewith means for regulating the fuel supply and the compressor has fluid actuated unloading means, comprising, in combination, a pivoted control member, means operatively connecting said control member to the means for regulating the fuel supply of the engine, a pressure responsive device for moving said control member and operable by pressure fluid supplied thereto to actuate said pivoted control member to effect a progressive reduction in fuel supply to the engine, means for continuously supplying fluid discharged by the compressor to said pressure responsive device, a second pressure responsive device for moving said control member and operable by pressure fluid supplied thereto further to actuate said pivoted control member to effect a reduction in fuel supply to the engine to cause operation of the latter at an idling speed, and valve means controlled by said first pressure responsive device and including a ball valve for controlling the supply of fluid to said second pressure responsive device and a plunger for actuating said ball valve and controlling the venting of fluid from said second pressure responsive device.
